UNITED STATES PATENT OFFICE.

TIMOTHY STEBBINS, OF DAVENPORT, IOWA, ASSIGNOR TO RED JACKET MANUFACTURING COMPANY, OF DAVENPORT, IOWA, A CORPORATION OF IOWA.

THREE-WAY VALVE.

1,053,327.

Specification of Letters Patent. Patented Feb. 18, 1913.

Application filed March 18, 1912. Serial No. 684,571.

To all whom it may concern:

Be it known that I, TIMOTHY STEBBINS, a citizen of the United States, residing at Davenport, in the county of Scott and State 5 of Iowa, have invented new and useful Improvements in Three-Way Valves, of which the following is a full, clear, and exact description.

My invention relates to three-way valves, 10 and particularly those used in connection with pumps at a point, above the cylinders, where the water is diverted to a trough or tank or other receptacle.

The object of my invention is to provide 15 a suitable packing for the part of the valve engaging the inner circumference of the central chamber of said casing, and to so construct the retaining or carrying devices for the packing or shoe thereof that the 20 means for keeping the latter yieldingly pressing outward against said shell, that it will not bind nor depend upon the water pressure back of it to make a water-tight connection with the openings of the pipe 25 stubs which it is adapted to close. This I accomplish by the means hereinafter fully described, and as particularly pointed out in the claims.

In the drawings: Figure 1 is a side view 30 of the casing embodying my invention. Fig. 2 is a vertical section therethrough. Fig. 3 is a vertical section at right angles to that shown in Fig. 2, taken on dotted line 3—3, Fig. 1. Fig. 4 is a detail view of the valve 35 proper separated from the casing.

Referring to the drawings, A represents the central cylindrical chamber of the T-shaped casing of my invention the axis of which is horizontal and closed at one end a, 40 and structurally open at the other. The open end is interiorly screw-threaded and engaged and closed by the threaded flange b of a suitable head B, and the center of this head has a suitable bearing c, that alines 45 with bearing c' in the opposite closed end of the said chamber, for the journals of the valve-spindle C. The inner circumference of this chamber A, is bored out smooth, and the axes of its alining vertical stubs d, d, and 50 its horizontal stub e intersect the center of length of the horizontal axis of the same. The opening of stub e into chamber A is contracted and less in diameter than the re-

mainder of the bore thereof. This provides an inner circumferential flange f whose 55 outer face is at right angles or transverse to the axis of said stub, and has the annular ring g of a flap-valve G seated against it, and held in place by a gland-nut E that is screwed into stub e until it impinges against 60 and clamps said annulus in such position that the flap-valve will permit water to flow into stub e from chamber A, but will prevent the return of the same.

The valve-spindle C between its journals 65 is made into a substantially O-shaped frame F, one side h of which is practically parallel to the axis of the spindle. At about its center of length the sides of this frame F, are provided with transverse openings; the 70 side h thereof, preferably, having a rectangular opening and the opposite side having a circular opening alining therewith. These openings guide the stem I of a segmental plate J; the square part of said stem being, 75 preferably, thicker than the remainder of its length and adapted to fit and slide in the square opening in side h and the cylindrical part of the stem extending into and having sliding engagement in the round 80 opening in the opposite side of the frame F. A coil expansion-spring K surrounds the stem between the sides of frame F, and presses the segmental plate J radially outward. Now, this segmental plate, preferably, corresponds in length to frame F, and its segmental width corresponds to the diameter of the openings leading from the bore of the chamber A, into the alining 85 stubs of the casing. This plate is, preferably, rectangular and its edges are correspondingly flanged outward and form the confines of a seat k, for a correspondingly curved segmental shoe or packing M, made of sole-leather or other suitable material. 90 The dimensions of this shoe are such that it fits snugly in the seat k, bounded by the flanges of said plate, and, in view of the even pressure of spring K against the shoe the latter will not rock in its seat, or bind, when 100 being moved in either direction. At one limit of its movement it is designed to close the upper stub of the casing, and thus direct the water up through the lower alining stub and out through the horizontal stub, 105 and when at the limit of its downward

movement, it closes the opening leading into the horizontal stub and the water then flows through the alining stubs.

What I claim as new is:

- 5 1. A three-way valve comprising a suitable T-shaped casing having a central chamber, in combination with a valve-spindle journaled in the ends of the central chamber and comprising an O-shaped frame between its journals, a transaxial valve-stem guided in transverse openings in opposite sides of said O-shaped frame, a coil spring surrounding said stem between said sides and normally pressing said stem radially outward, a valve comprising a plate on the outer end of said stem having its edges flanged outward, and a shoe seated against the outer face of said plate and confined by said flanges.
- 10 2. A three-way valve comprising a suitable T-shaped casing having a central chamber, and three stubs, the intermediate one of which has a suitable closure in its bore for preventing back flow, in combination with a valve-spindle journaled in the ends of said chamber, a valve having a stem journaled in and adapted to move in transverse bearings in said spindle, a shoe, a holder on the outer end of said stem adjacent the inside wall of said chamber between which and the wall of said chamber said shoe is seated, and means engaging said stem and spindle for pressing the latter radially outward into yielding contact with the bore of said chamber.
- 15 3. A three-way valve comprising a suitable T-shaped casing having a central chamber, and three stubs the intermediate one of which has a restricted opening commun-

cating therewith, and a suitable closure for said opening preventing back flow, of a valve-spindle journaled in the ends of said chamber, a valve having a stem journaled in and adapted to move in transverse bearings in said spindle, a shoe, a holder on the outer end of said stem adjacent the inside wall of said chamber between which and the wall of said chamber said shoe is seated, and means engaging said stem and spindle for pressing the former radially outward.

4. In a three-way valve, the combination with a T-shaped casing having a central chamber, and three stubs the intermediate one of which has a restricted opening communicating therewith, a gland-nut screwed into said intermediate stub, a flap-valve clamped in place by said gland-nut to provide a suitable closure for said restricted opening preventing back flow into said chamber, of a valve-spindle journaled in the ends of said chamber and comprising an O-shaped frame between its journals, a transaxial valve-stem guided in transverse openings in opposite sides of said frame, a coil spring surrounding said stem between said sides and normally pressing said stem outward yieldingly against the inner circumference of said chamber, a valve comprising a plate on the outer end of said stem, and a shoe seated or retained against the outer surface of said plate.

In witness whereof I have hereunto set my hand this 5th day of March, 1912.

TIMOTHY STEBBINS.
